SCRIBING ASSEMBLY

Zisu Israel, Winnipeg, Manitoba, Canada

Application February 9, 1951, Serial No. 210,195

3 Claims. (Cl. 33—41)

1

My invention relates to new and useful improvements in scribing assemblies, more particularly to scribing assemblies used in conjunction with either a conventional straight-edge rule or a set square, an object of my invention being to provide a device of the character herewithin described whereby a line or mark may be inscribed upon paper, wood, or the like, with the rule or square in position thereby eliminating the necessity for using a separate pencil or scribing implement.

A still further object of my invention is to provide a device of the character herewithin described in which the scribing assembly can be rotated clear of the edge of the rule or square thereby enabling the latter to be used in the conventional way.

Another object of my invention is to provide a device of the character herewithin described which includes means for maintaining the scribing assembly parallel with the edges of said rule or square during the operation thereof.

A further object of my invention is to provide a device of the character herewithin described which includes an indicating marker projecting rearwardly from the scribing assembly, which marker indicates, by means of a conventional measuring indicia engraved upon the rule or square surface, the exact position or distance that the scribing point has travelled thereby permitting a line of a given length to be scribed.

Still another object of my invention is to provide a device of the character herewithin described which includes an actuating finger grip positioned upon the scribing assembly so that twisting or canting of said assembly is eliminated.

A still further object of my invention is to provide a device of the character herewithin described which is economical in manufacture, simple in operation, and otherwise, well suited for the purpose for which it is designed.

With the foregoing objects in view, and such other objects and advantages as will become apparent to those skilled in the art to which this invention relates as this specification proceeds, my invention consists essentially in the arrangement and construction of parts all as herein-after more particularly described, reference being had to the accompanying drawings in which:

Figure 1 is a fragmentary perspective view of a straight-edge with one embodiment of my device in situ thereupon.

Figure 2 is a perspective view of a set square with an alternative embodiment of my device in situ thereupon.

2

Figure 3 is a vertical section of the embodiment of my device shown in Figure 1.

In the drawings like characters of reference indicate corresponding parts in the different figures.

Attempts have been made in the past to provide either a straight-edge or set square with a scribing device incorporated therein in order to facilitate the scribing of lines upon such material as paper, wood, or the like. The majority of these previous devices suffer from several disadvantages the most important of which is that, once incorporated, they interfere with the normal use of the straight-edge or set square.

Furthermore, the prior devices do not include efficient means for varying the pressure upon the scribing point neither do they incorporate efficient sliding actions which will permit ready movement of the scribing assembly along the

straight-edge or set square yet at the same time prevent undesirable canting in relation to the sliding surface with the subsequent jamming of the scribing device occurring.

My invention overcomes these disadvantages as well as providing a scribing assembly which is adapted for use upon either a conventional straight-edge or a set square commonly used in woodworking and the like.

Proceeding, therefore, to describe my invention in detail, it will be seen upon reference to the accompanying drawings that I have illustrated in Figure 1 a straight-edge 10 having a front edge 11 upon which may be engraved suitable measuring indicia as indicated at 12. The rear edge 13, also engraved with indicia 12' corresponding exactly with the indicia 12 upon the forward edge thereof, is also provided with an outstanding portion 14 bearing three recessed apertures 15 within which the finger tips of the operator may be placed in order to steady the straight-edge during operation of my scribing assembly.

My scribing assembly or block, collectively designated 16 includes a base portion 17 and a hinged portion 18. The base portion 17 comprises a substantially rectangular plate 19 having a pair of lugs 20 upstanding from the upper surface thereof between which is pivoted for limited vertical rotation, the aforementioned hinged portion 18, by means of pin 21.

The scribing block 16 is adapted to slide longitudinally along the upper surface 22 of the straight-edge 10, means being provided upon said upper surface to maintain said scribing block in position and in parallel relationship with the edges 11 and 13 of the straight edge. The means

comprise a pair of spaced and parallel strips 23 and 24 secured to the upper surface 22 and extending longitudinally along the straight-edge. The inner edges 25 of the strips incline downwardly and outwardly thereby forming, together with the upper surface of the straight-edge bounded by the strips, a mortise groove 26.

The aforementioned base portion 17 has formed upon the underside thereof, a tenon 27, the dimensions of which are designed to permit the sliding engagement of same within the aforementioned mortise groove 26 but without any appreciable side play therebetween. Further lateral stability is given to the base portion 17 by the incorporation thereupon of a down-turned lip 28 situated upon the rear edge of the plate and slidably bearable against the outer edge 29 of the aforementioned strip 23.

The hinged portion 18 also comprises a substantially rectangular plate hinged between lugs 29 as hereinbefore described and being provided with a double-stepped under surface 30 also to provide lateral stability to the scribing block. The double-stepped under surface includes an upper step 31 which rests upon (when in the position shown in Figure 1) the upper surface 32 of the aforementioned strip 24. The vertical wall of the lower step 33 slidably bears against the outer edge 34 of the other strip 24 thereby complementing the action of the downturned lip 28 as hereinbefore described.

A scribing point 35 is situated upon the front end 36 of the hinged portion and extends downwardly therethrough and is adapted to lie adjacent the edge 41 of the straight-edge, projecting slightly below the under surface of the straight-edge so that it will engage the surface upon which the straight-edge is resting. This scribing point may either take the form of a sharpened steel pin (for use upon wood or metal) or a lead pencil point which may be grasped in a conventional chuck (not illustrated).

A finger grip 37 projects upwardly from the upper surface of the hinged portion 18 to permit sliding movement of the scribing block along the straight-edge, this grip being positioned so that it may control the pressure of the scribing point as well as eliminating any canting of the scribing block within the mortise slot 26. In operation, the straight-edge is positioned upon the work to be inscribed whereupon the finger tips are placed within the apertures 15 thus holding the straight-edge securely in position. The hinged portion 18 of the scribing block is then raised and the scribing block slid along the mortise groove 26 to the position at which the scribed line is to be commenced whereupon the hinged portion is lowered to the position shown in Figure 1.

The scribing block is then moved along the straight-edge by means of the actuating finger grip 37, downward pressure being applied to the hinged portion so that the scribing point marks the material upon which the straight-edge is being used. In order to facilitate the accurate measurement of the line being scribed, I have provided an indicating marker 38 extending rearwardly from the down-turned lip 28 and bearing upon the indicia scale 12' provided upon the rear edge of the straight-edge. As this scale corresponds to the front scale 12, and as the scribing point 35 is in transverse alignment with the indicating marker 38, the indicating marker allows the operator to inscribe a line or mark of a predetermined length.

Proceeding now to describe the alternative embodiment illustrated in Figure 2 of the accompanying drawings, it will be seen that I have shown a conventional set square 39, having a stock 40 and a straight-edge 41 situated at right angles thereto.

The straight-edge 41 is provided with a scale 42 upon the front edge 43 thereof and a corresponding scale 44 upon the rear edge 45 thereof in a similar manner to the straight-edge hereinbefore described in the previous embodiment.

My scribing assembly or block collectively designated 46 in this embodiment, also includes a base portion 47 and a hinged portion 48 pivotally secured for limited vertical rotation between lugs 49 upstanding from a substantially rectangular plate 50 from which the aforementioned base portion 47 is formed. A tenon 51 is provided upon the under surface of plate 50 slideably engageable within a mortise groove 52 formed within the straight-edge 42 of the square, it being understood that the dimensions of the tenon and mortise groove are such as to permit easy sliding movement without undesirable side play existing.

The hinged portion 48 comprises a substantially rectangular plate hinged as aforesaid and is provided with a pair of scribing points 53 extending downwardly therefrom adjacent the front edge 43 of the straight-edge in a similar manner to the scribing point 35 hereinbefore described.

A finger grip 54 upstands from the hinged portion and enables the operator to slide the scribing assembly along the straight-edge and to enable the operator to supply sufficient pressure to the scribing points 53 to cause them to inscribe a line on the surface of the work upon which the set square is being used.

The operation of this embodiment is similar to that hereinbefore described but it will be noted that, when utilized with a set square, the two scribing points 53 provided permit the inscribed line to commence substantially adjacent the butt end 55 of the square, an important consideration when the device is being used in wood or metal working. An indicating marker 56 is also provided extending from the rear edge of the base portion 50 which acts in a similar manner to the marker 38 hereinbefore described.

In conclusion, it will be seen that I have provided stops 57 at the extremities of the straight-edge in order to prevent undesirable displacement of the scribing block therefrom.

Since various modifications can be made in my invention as hereinabove described, and many apparently widely different embodiments of same made within the spirit and scope of the claims without departing from such spirit and scope, it is intended that all matter contained in the accompanying specification shall be interpreted as illustrative only and not in a limiting sense.

What I claim as my invention is:

1. An assembly for the inscribing of lines on material such as paper, wood or the like comprising in combination a straight-edge, a scribing block slideably engageable upon the upper surface of said straight-edge, means upon said upper surface to maintain said scribing block in parallel relationship with the sides of said straight-edge, said scribing block including a hinged portion and a base portion, and a scribing point extending downwardly from said hinged portion adjacent one of said sides, said means including a pair of spaced and parallel strips secured longitudinally to said straight-edge, the inner edges of said strips inclining downwardly

and outwardly to form, with said upper surface, a mortise groove, a tenon formed upon the under-side of said base portion slideably engageable with said groove, said base portion comprising a substantially rectangular plate, a down-turned lip upon the rear edge of said plate slideably bearable against the outer edge of one of said strips, said hinged portion being pivotally secured to said base portion, the underside of said hinged portion being double-stepped, the vertical wall 10 of the lower of said steps being slideably bearable against the outer edge of the other of said strips.

2. An assembly for the inscribing of lines on material such as paper, wood or the like, comprising in combination a straight-edge, a scribing block slideably engageable upon the upper surface of said straight-edge, means upon said upper surface to maintain said scribing block in parallel relationship with the sides of said straight-edge, said scribing block including a hinged portion and a base portion, and a scribing point extending downwardly from said hinged portion adjacent one of said sides, said hinged portion comprising a substantially rectangular plate hinged for partial vertical movement to said base 25 portion, the underside of said hinged portion registering against the upper surface of said straight-edge thereby controlling the depth of penetration of said scribing point, said means including a mortise groove extending longitudinally along the upper surface of said straight-edge and a tenon formed upon the underside of said base portion slideably engageable with said groove.

3. An assembly for the inscribing of lines on material such as paper, wood or the like, comprising in combination a straight-edge, a scribing block slideably engageable upon the upper surface of said straight-edge, means upon said upper surface to maintain said scribing block in parallel relationship with the sides of said straight-edge, said scribing block including a hinged portion and a base portion, and a scribing point extending downwardly from said hinged portion adjacent one of said sides, said base portion including a substantially rectangular plate, lugs upstanding from said plate between which said hinged portion is pivotally secured, and an indicating marker extending rearwardly from said plate adjacent the upper surface of said straight-edge, said means including a mortise groove extending longitudinally along the upper surface of said straight-edge and a tenon formed upon the underside of said base portion slideably engageable with said groove.
